UNITED STATES PATENT OFFICE.

SAMUEL P. HOWE, OF MERCHANTVILLE, NEW JERSEY, ASSIGNOR TO CAMDEN FORGE COMPANY, OF CAMDEN, NEW JERSEY, A CORPORATION OF NEW JERSEY.

FURNACE-DOOR.

No. 902,966.

Specification of Letters Patent.

Patented Nov. 3, 1908.

Application filed April 28, 1908. Serial No. 429,694.

To all whom it may concern:

Be it known that I, SAMUEL P. HOWE, a citizen of the United States, residing in Merchantville, New Jersey, have invented 5 certain Improvements in Furnace-Doors, of which the following is a specification.

One object of my invention is to provide a door of the type employed in connection with open hearth or puddling and similar furnaces, which shall be of such a construction as to require a minimum of repairs and possess a relatively long life under operating conditions.

I further desire to provide a furnace door 15 which shall be of a relatively simple construction and capable of being conveniently removed and replaced or repaired when necessary; it being desired in addition that the furnace door shall include a system of cooling conduits or pipes, which shall not only keep down the temperature of the door but shall also serve as a portion of the door supporting means.

These objects and other advantageous ends 25 I secure as hereinafter set forth, reference being had to the accompanying drawings, in which:—

Figure 1, is a front elevation of my improved furnace door, and Fig. 2, is a side 30 elevation of the door illustrated in Fig. 1.

In the above drawings A is a plate or block of refractory material such as fire brick, usually of substantially rectangular shape and forming the main portion of the 35 furnace door. At a suitable point in this refractory block there is provided a peep hole a around which is a small frame a' supporting a slide a^2 which may be drawn over or removed from the hole at will.

40 In each of the four edges of the block there is a groove or recess extending the whole length thereof and serving on the two sides and bottom of the door for the reception of a water pipe b for cooling the same.

45 This pipe is connected at one end to a supply pipe b' and there is usually a valve b^2 between it and said supply for controlling the flow of water. The other end of this pipe b is extended above the door, then 50 turned at right angles away from the door, and then extended downwardly in a length b^3 . This latter projects into a suitable drain pipe or receptacle c preferably having a funnel shaped mouth c' ;—it being noted 55 that this latter pipe, as well as the section

b^3 extending into it, are so arranged as to be parallel to the line of movement of the furnace door and consequently said section b^3 is at all times in position to discharge 60 into the drain pipe c regardless of whether the furnace door is open or closed.

For supporting the furnace door I provide a cross bar d extending from the top of the block A and forked at each end so as to embrace the adjacent portions of the water pipe 65 b . Each of these forked ends is provided with a set screw d' whereby said bar may be rigidly connected to these pipes, and there is at the middle of the cross bar an eye-bolt d^2 or other suitable receptacle for 70 the end of a suspending chain.

With the above described arrangement of parts it will be noted that the block of refractory material forming the main portion of the furnace door is mounted in a frame, 75 three sides of which are formed by the water pipes while its top is formed by the cross bar connected to the suspending means. Moreover, the water pipes are completely concealed and protected in the grooves in 80 the sides and bottom of the said refractory block which, being provided with a groove in its top surface, may be reversed in its frame if its bottom edge should become 85 burned away.

I have found by practical experience that a door constructed as described has a relatively long life and requires but little repair, one reason for this being that the water pipes are capable of maintaining the 90 single block at a relatively low temperature owing to its continuity, while in addition this latter is so supported in the frame that its free expansion under changes of temperature is not interfered with.

95 I claim:—

1. A furnace door consisting of a single substantially rectangular reversible structure of refractory material having longitudinally extending grooves in its edges, 100 with a supporting frame for said structure extending into said grooves.

2. A furnace door consisting of a substantially rectangular structure of refractory material, having longitudinally extending grooves in its edges, with a supporting frame for said door extending into 105 said grooves, a portion of said supporting structure consisting of water pipes.

3. A furnace door consisting of a body 110

of refractory material, a supporting frame therefor consisting of a cross bar for attachment to supporting means, and a water pipe attached to said cross bar and directly carrying the body of refractory material.

4. A furnace door consisting of a substantially rectangular structure of refractory material having longitudinally extending grooves in its edges, a water pipe extending in and protected by the grooves in the sides and bottom of said structure, a cross bar extending across the top of said structure and in engagement with the water pipes, with means for attaching a suspending device to said cross bar.

5. A furnace door consisting of a single integral block of refractory material provided with grooves in its edges, a frame for supporting said block consisting of a water pipe extending in and protected by said grooves, and means for attaching a suspending device to said frame.

6. A furnace door consisting of a single integral block of refractory material having longitudinally extending grooves in its four edges, a supporting frame for said

block consisting of a water pipe extending in and protected by the grooves at the sides and bottom of the block, a cross bar extending from the top of the block and removably connected to the water pipes above the sides of the block, and means for connecting a suspending device to said cross bar.

7. A furnace door consisting of a single integral block of refractory material having longitudinally extending grooves in its four edges, a supporting frame for said block consisting of a water pipe extending in and protected by the grooves at the sides and bottom of the block, a cross bar extending over the top of the block and removably connected to the water pipes, and means for connecting a suspending device to said cross bar, said block being reversible in the frame.

In testimony whereof, I have signed my name to this specification, in the presence of two subscribing witnesses.

SAMUEL P. HOWE.
